UNITED STATES PATENT OFFICE.

MAX HASAIT, OF DRESDEN, GERMANY, ASSIGNOR TO AKTIEBOLAGET ARS, OF STOCKHOLM, SWEDEN, A CORPORATION.

ADJUSTABLE SCENE PORTAL IN THEATERS.

Application filed May 26, 1921. Serial No. 472,777.

To all whom it may concern:

Be it known that I, MAX HASAIT, subject of Germany, residing at Dresden, Germany, have invented certain new and useful Im-
5 provements in Adjustable Scene Portals in Theaters, of which the following is a specification.

This invention relates to an adjustable scene-portal in theaters and differs from 10 similar portals heretofore known by the portal surrounding the scene-opening in the form of an adjustable frame, the opening of which can be increased or reduced, the members by means of which the sides of the 15 frame are moved together or apart being invisible from the auditorium and a foot-bridge being raised and lowered upon the adjustment of the opening of the portal, while foot-bridges and balustrades are 20 drawn forth from lighting galleries provided in the sides of the portal, said foot-bridges being adapted to support different apparatus and scene-shifters.

Scene-portals have hitherto only been used 25 to increase or reduce the scene-opening and consist generally of thin walls movable sideways and in front of which draperies are placed which may be raised and lowered thus increasing or decreasing the scene-opening. Such an arrangement is connected 30 with the inconvenience that the workman operating the lighting controller cannot look over the scene from his cabin, since in case of a very reduced scene-opening the scenery placed near the portal will hide the view. Another inconvenience connected with such 35 a flat frame consists in that the foot-bridge is fixed to the portal and placed so high, that in the highest position of the draperies it is concealed to the spectators, and on account thereof a scene passing on in a closed 40 room covered by a ceiling cannot be lighted by means of lighting apparatus located on the foot-bridge, because of the fixed foot-bridge being placed too high above the 45 ceiling.

By the aid of a frame constructed at all sides of wide members the advantage is obtained that foot-bridges may be disposed 50 extending, even in case of the smallest portal-opening, immediately to the scenery, placed near the portal, it being thus possible to look over and lighten the scene from the foot-bridge. The fireman may be positioned on the stage-floor within the side of

the frame and is able to look over the scene completely from said place, and in case of danger of fire he can move himself speedily to the scene through a door-opening in the side of the frame without being compelled 60 to pass through the scenery located at the portal. Above him the inspector of lighting can get out from his cabin to the foot-bridge to operate the lighting apparatus thereon and look over the decreased scene. This applies also to the stage-manager. On foot-bridges for the lighting galleries located still higher lighting apparatus may be disposed by means of which the scene may be lighted even in its least size, and besides the 65 scene can be lighted beneath the ceiling from the upper, lowered foot-bridge. The controller may for instance be located on one of the foot-bridges and thus be carried on upon the adjustment of the parts of the 70 portal. Said apparatus may by means of conductors, extensible shafts or pipes be connected with the regulating resistance, or otherwise the latter may be carried on. Owing thereto the person managing the 75 controller has always, even in case of the smallest portal-opening, the controller in immediate proximity. Moreover other lighting apparatus and scene-machines may be placed on the movable parts of the portal 80 and connected with devices by means of which said apparatus are managed. The portal frame may be of any shape and its parts may be connected by joints of any 85 type. The frame may be coated with stuff, 90 wood, metal or other materials.

In connection with the above-mentioned advantages of great importance in a theater the invention brings about a portal of artistic effect well bounding the scene-opening, 95 without displaying for the spectators the parts by means of which the different members of the portal are moved relatively to each other.

An embodiment of the invention is illustrated in the accompanying drawing in which—

Fig. 1 is a perspective view of the one half of a scene-portal arranged according to the invention and viewed from the auditorium. 105 Fig. 2 is a section on line *a*—*b*—*c* in Fig. 1. Fig. 3 is a section on line *f*—*g* in Fig. 1. Fig. 4 is a section on line *a*—*b* in Fig. 1 and Fig. 5 is a section on line *d*—*e* in Fig. 1.

Referring to the drawing, 1 and 2 are a 110

fore and a rear frame-work respectively parallel to each other, and to the middle part of which a floor 3 for instance of wood is rigidly attached and provided at the ends of 5 the frame-works with recesses 9. 4 designates the lower side of the upper border of the portal-opening, and above said lower side a slide 5 is attached to the side 11, 11^a of the portal. 14 is a fixed gallery, 13 is a 10 balustrade and 12 is a foot-bridge, the two last-named being connected to the side of the portal and carried along by the same, when moved in the direction of arrow *h* in Fig. 1 to the position 16^a indicated by stippled lines in Fig. 1. 15 is the door intended for the fire-man. 17 and 17^a designate a box-shaped frame resting on the stage-floor and forming the lower border of the portal-opening. Placed below the frame are the 20 lower foot-lights 21, the prompter's box and the lighting box. 19 is the stage-floor which supports the scenery 22 above which a ceiling 6 is located. Placed below the latter is a lighting-apparatus 20 capable of lighting 25 the scene. 3^a is a transverse stay connecting the frame-works 1 and 2. 7 and 7^a designate a coating of metal, stuff, wood or the like connected with the lower side 4 and directed towards the auditorium. 23 is a 30 wall covering the parts of the side 11, 11^a of the portal when drawn out. The wall 23 may be stationary or movable. 10 designates guides along which the slide 5 is sliding when moved.

35 As will appear from Fig. 1, the scene-opening can be reduced from the positions of the parts 4 and 11^a shown in said figure by full lines to the positions of the same parts indicated by 16 and 16^a. The side 11, 40 11^a of the portal is preferably, to effect its movement, supported by rollers 25, Fig. 1, and the raising and lowering of the frame-works 1 and 2 may be effected by means of hoisting ropes 26 or the like.

45 What I claim as new and desire to secure by Letters Patent of the United States is:—

1. Adjustable scene-portals in theaters, comprising an upper portal part movable up 50 and down, a foot-bridge connected with the said upper portal part at the middle thereof, recesses provided in said foot-bridge at the ends of the portal part, and side parts of the portal movable to and fro in said recesses.

2. Adjustable scene-portals in theaters, comprising an upper portal part movable up and down, a foot-bridge connected with the said upper portal part at the middle 60 thereof, recesses provided in said foot-bridge at the ends of the portal part, side parts of the portal movable to and fro in said re-

cesses, and lighting apparatus connected with said upper portal part.

3. Adjustable scene-portal in theaters, 65 comprising an upper portal part movable up and down and composed of frame works, a foot-bridge connected with the frame works at the middle of said portal part, recesses provided in said foot-bridge at the 70 ends of the portal part, and side parts of the portal movable to and fro in said recesses.

4. Adjustable scene-portal in theaters, 75 comprising an upper portal part movable up and down, a foot-bridge connected with said upper portal part at the middle thereof, recesses provided in the foot-bridge at the 80 ends of the portal part, side parts of the portal movable to and fro in said recesses, guides located beneath and connected with the upper portal parts and slidable slides connected with the side parts of the portal and entering, upon the movements of said 85 side parts below the foot-bridge.

5. Adjustable scene-portal in theaters, 90 comprising an upper portal part movable up and down, a foot-bridge connected with said upper portal part at the middle thereof, recesses provided in the foot-bridge at the 95 ends of the portal part, side parts of the portal movable to and fro in said recesses, and foot-bridges and balustrades connected with the movable side parts and carried along with the same.

6. Adjustable scene-portal in theaters, 100 comprising an upper portal part movable up and down, a foot-bridge connected with said upper portal part at the middle thereof, recesses provided in the foot-bridge at the 105 ends of the portal part, side parts of the portal movable to and fro in said recesses, a stage-floor and a box-shaped frame placed on the stage-floor between the side parts of the portal and forming a lower border of the same.

7. Adjustable scene-portal in theaters, 110 comprising an upper portal part movable up and down, a foot-bridge connected with said upper portal part at the middle thereof, recesses provided in the foot-bridge at the 115 ends of the portal part, side parts of the portal movable to and fro in said recesses, and foot-bridges connected with the movable side parts and carried along with the same, the foot-bridges being capable of supporting lighting and driving apparatus and appliances.

In testimony whereof I affix my signature in presence of two witnesses.

MAX HASAIT.
